ATTORNEYS

UNITED STATES PATENT OFFICE.

HERMAN FREDERICK NEHR, OF NEW YORK, N. Y.

DESIGN FOR A ROSARY.

No. 37,659.

Specification for Design.

Patented Nov. 14, 1905.

Application filed August 31, 1905. Serial No. 276,641. Term of patent 14 years.

To all whom it may concern:

Be it known that I, HERMAN FREDERICK NEHR, a citizen of the United States, and a resident of the city of New York, borough of Brooklyn, in the county of Kings and State of New York, have invented a new, original, and ornamental Design for a Rosary, reference being had to the accompanying drawing.

The figure is a perspective view of a rosary, showing my new design.

I claim—

The ornamental design for a rosary as shown.

HERMAN FREDERICK NEHR.
